DOOR FRAME

Alfred Benjamin Carper, Eugene, Oreg.

Application January 22, 1945, Serial No. 573,889

15 Claims. (Cl. 20—12)

1.

This invention relates to a frame for incorporation in a building structure to receive a door, window or similar closure. While not restricted in its application to a door frame, it is best illustrated in connection with a door frame, and will be so described in this specification. Reference to a door frame will, therefore, be understood as illustrative rather than restrictive, and to be intended to include other such frames.

The present invention is a continuation in part of my abandoned application Serial No. 536,381, filed May 23, 1944. In particular the construction of Figure 1 corresponds to the construction disclosed in my prior application, referred to above, and the construction of Figures 2 and 3 embodies similar principles in different constructions.

The usual practice has been to install a door frame of fixed size in place in the rough framing or studding, employing shims and nails to secure the frame rigidly to the studding, and then to fit a stock size door to this frame by hand sawing or planing the door to fit. This procedure, together with hand-fitting of hinges and cooperating lock parts, made door installation a slow, painstaking, and expensive job. Recognizing the difficulties of installing a fixed frame, others have proposed installation of each jamb individually, but a difficulty of another sort then arises, namely, that of obtaining proper relative location of the several independent jambs, and of avoiding unsightly and unsanitary gaps between jambs at the corners. Even so, hand fitting is still required, for if the jambs were prefitted with seats for hinges and striker plate, the installation difficulties would be magnified.

The principal object of my invention is to simplify the installation of both the frame and the door. More particularly with my invention the door frame may be manufactured, the door cut square and to size, and all hardware fitted at the shop or factory by the use of modern machinery, and, when installed, the door frame may be quickly and easily plumbed and adjusted to a very accurate fit between the edges of the door and the frame, with just such clearance at both sides and at the top and bottom as may be desired, and without the possibility of gaps at the corners. In effect, the frame is now fitted to the door, rather than the reverse, as heretofore.

It is known to provide door frames, certain elements of which are adjustable, after the door and frame have been installed, to accommodate shrinkage or swelling of the door or settling of the building. My invention is not primarily directed to the latter purposes, but is directed pri-

marily to the objects hereinbefore set forth; nevertheless by the use of my invention adjustments for shrinkage, swelling, or settling may be made without difficulty at any time after installation.

In the accompanying drawings my invention is shown in various representative forms, including one now particularly preferred by me, it being understood, however, that the invention is not restricted to any particular form or arrangement except as is required by the terms of the claims which are to be found at the end of this specification.

Figure 1 is an isometric view of an exterior door frame and door, embodying my invention, parts being broken away for better illustration.

Figure 2 is a corner detail of a modified construction.

Figure 3 is an elevation of an interior door incorporating the presently preferred form of construction, with associated building elements shown broken away or in section.

The invention may be incorporated either in an exterior door, as in Figure 1, or in an interior door, as in Figure 3, and the preference expressed for the construction of Figure 3 is not because of that difference, but because of the somewhat more commercially practicable manner of connecting and assembling the several jambs, and of adjusting them upon installation relative to one another and to the supporting studding, as will appear from the descriptions of the individual forms. It will be remembered, then, that the form of construction illustrated in Figure 1 may be incorporated in an interior door, and conversely, the form of construction of Figure 3 may be incorporated in an exterior door. In an exterior door the sill is first located and leveled, and the door frame should be supported and located from the sill, leaving clearance beneath the lower ends of the side jambs. In the interior door no sill is employed, hence one of the side jambs is initially located for the purpose of locating the other elements of the frame.

In Figure 1 the sill is shown at 14, and the frame is completed by spaced side jambs 1 and 2, and the head jamb 3 connecting their upper ends. Since the spacing between the side jambs 1 and 2 may have to vary, the lower ends of the side jambs are dadoed or transversely channelled, as indicated at 13, to receive the ends of the sill 14, which are purposely made somewhat shorter than would be required when received in these channels 13 to space the jambs 1 and 2 before installation by the exact distance deemed necessary. The

dadoes 13 are wholly concealed when installation is complete, and may be filled with waterproof glue or with calking material at the time of installation, to secure the side jambs and sills together and to prevent entrance of foreign matter or moisture.

The sill 14 having been located and secured in place, the next step is to locate the side jamb 1, this being the jamb which carries the hinges 15 supporting the door 9. One end, preferably its upper end, is spaced from the adjoining studding (see Fig. 3) by a spacer 11, which preferably extends across the entire width of the jamb. With the jamb 1 plumb, at least in a direction perpendicular to the general plane of the door frame, its upper end is secured in this position by screwing home the screw 10 which passes through the jamb, and which may pass through or near the spacer 11 into the studding. Its lower end is then plumbed both ways, and is secured in this position by screws 6 passing through the jamb and into the studding. Preferably resilient means, illustrated as the coil springs 12, are employed between the back faces of the jamb and the studding surrounding the screws 6, these springs serving to space the jamb away from the studding, while yet permitting the screws 6 to draw the jamb towards the studding. These springs will also force the jamb away from the studding, upon slackening off the screws.

With the jamb 1 thus located, and with a leaf of the hinge 15, or at least the seat therefor, previously fitted at the factory, the door 9 will swing at the proper clearance above the sill 14, and at the proper clearance beneath the head jamb 3, which at this end rests upon the upper end of the jamb 1, and is held against separation therefrom, such as would leave a gap.

The next step is the location and securement of the jamb 2, opposite the jamb 1 which has now been secured in place. The jamb 2 is adjustable in its spacing relative to the jamb 1 at both ends. It is adjustable at its lower end by reason of the adjustment accorded by the sill being cut short of the bottom of the channel 13. It is adjustable at its upper end by reason of the fact that the head jamb 3 is connected to the jamb 1 by means which permit some limited adjustment lengthwise of the head jamb 3, but which prevents any separation of the jambs 1 and 3. For example, screws 4 provided with washers 5 pass through holes in the head jamb 3 and into the end of the side jamb 1. These holes are either slotted longitudinally of the head jamb, corresponding to the holes 20 as seen at the left in Figure 1, or are oversize holes permitting limited but sufficient adjustment relative to the smaller shank of the screws 4. The screws 4 are sufficiently tight to hold side jamb 1 and head jamb 3 in close frictional contact against separation, but are loose enough to permit the head jamb to slip across the end of the side jamb 1 when the screws 6 are tightened.

By such means the spacing between the side jambs 1 and 2 is adjusted, with just sufficient side clearance for the door, and the side jamb 2 is plumbed. It, too, is secured to its studding by screws 6 backed by the springs 12.

During the location of the side jamb 2, or thereafter, the head jamb 3 is leveled, and it will be observed that whereas its right end, as seen in Fig. 1, rests upon the abutted upper end of the side jamb 1, its left end abuts the side face of the side jamb 2, and the two are connected in this relationship by screws 7 having washers 8, the screw shanks passing through slots or enlarged

holes 20, which hold the head jamb 3 against accidental slippage, and against any possibility of separation from the side jamb 2, but afford the ability to adjust up or down the left end of the head jamb relative to the side jamb 2, for leveling, and to give the required top clearance for the door.

It is usually not necessary to secure the head jamb 3 to the rough framing or header above it, 10 for the reason that it will be held, as will also the jambs 1 and 2, in adjusted position by securement of the casing elements 18. However, if desired, securing means such as screws 6 and springs 12 may be employed to secure also the head jamb.

The nailing of the casings 18 to the frame elements and to the studding securely and rigidly holds the frame in its proper position. If the casing 18 is nailed only to the studding, later 20 adjustment of the frame is facilitated, and the screws 6 and springs 12 or 23 will adequately secure the frame. Instead of using casings, the surface finish of the wall, such as lath and plaster, can be extended to lap onto the edges of the door 25 jambs and be fastened thereto; the joint can be concealed by a suitable moulding.

The frame having been thus installed the door 9 is hung, and if, as preferred, the hinges 15, the latch elements 16, and the striker plate 17 have 30 been fitted at the shop or factory, the several parts will match properly and the door is hung and ready for use in a minimum of time.

Since this is an exterior door a threshold 19 would normally be installed, after installation of the frame as described above, and its thickness would be taken into account in initially fitting the door at the factory. Also door stops 21 would be employed, and these may be either formed as part of the jambs or installed after installation 40 of the jambs. If formed as part of the jambs the matching jambs will be rabbeted, as indicated at the top of the side jamb 1, and at the left end of the head jamb 3, to receive the corresponding door stops 21, see Figure 2. When such door 45 stops are thus received in rabbets they will not prevent the desired relative adjustment of the jambs at the corners, within the general plane of the frame as a whole, but will prevent both separation of the jambs at the joint, and adjustment 50 of the jambs out of the common plane of the frame. It is possible, of course, to install the stops separately later, mitering their ends, if desired, and securing them in place to cover the heads of the screws 6 and 10.

55 The form shown in Figure 2 is in substance the same as is shown in Figure 1, except that at the joint illustrated, that between the head jamb 3 and side jamb 2, while the end of the head jamb still abuts the side face of the side jamb 2, the head jamb 3 is provided with an extension 32 which overlies the end of the side jamb 2, and which is provided with a hole into which is snugly fitted a dowel pin 31 projecting upwardly above and in prolongation of the end of the side jamb 2. Such a dowel pin (or pins) prevents relative 60 displacement of the jambs out of the general plane of the frame as a whole, or in a direction lengthwise of the head jamb 3 in this instance, but permits vertical adjustment of this end of the head jamb relative to the side jamb 2 without the possibility of separation such as would leave a gap at the corner. A similar dowel construction 65 may be employed at the opposite end of the head jamb, although here horizontally disposed to permit relative lateral adjustment between the side

jambs 1, thus connecting the head jamb, but preventing all other relative adjustments or separations between the two latter jambs.

The arrangement of Figure 3, except that it shows an interior instead of an exterior door, is substantially the same as that of Figure 1, and the same numerals have been applied to corresponding parts. In installing this frame, since there is no sill, the first step is to locate, plumb, and secure the hinge-mounting side jamb 1, which is done as before by securing the screw 10 through the jamb, through or near the spacer 11, and into the upright stud 22. Though the height is not determined in this instance by the sill and the channel 13, the height of the hinge seats is calculated in such manner as to give the door, say $\frac{5}{8}$ ", clearance at the bottom, if the jamb end rests upon the floor. If less clearance is desired, the jamb may be cut off as desired. Similarly, by reason of the previous location of the hinge 15, proper clearance at the top between the door and the head jamb 3 is assured. Again, as before, the lower end of the jamb 1 is plumbed and located and secured by the screws 6 reacting against the springs 23, which correspond to the springs 12, but which are formed as bowed leaf springs of some appreciable width and hence lateral stability, which have integral prongs 24, by means of which they may be preliminarily supported from the jamb.

The leaf springs 23 and their screws 6 will ordinarily retain the hinge-mounting jamb 1, thus located and plumbed, during further operations. However, if desired, the lower end of the jamb 1 may be secured temporarily against the possibility of disturbance by employing a temporary spacer 25 nailed in place at one or both edges of the jamb, and at the end opposite the spacer 11. This will more probably be found necessary when coil springs 12 are used, than with the leaf springs 23. The door may be hung as an aid in properly spacing the opposite side jamb 2 and the head jamb 3; the use of temporary spacers may be desired in certain cases where otherwise the door's weight would tend to compress the springs 23, and to dislocate at least the lower end of the jamb 1. Incidentally, the use of a spacer, as 11, at the lower end of the hinge-mounted jamb 1, instead of the upper end, was preferred, to avoid such compression, but since the weight of the door, when swung outwardly from the frame, would have a greater tendency to pull the frame askew if it were not solidly fastened at its upper end, it is preferred that the spacer 11 be located near the top of the jamb 1 in the vicinity of the upper hinge, to resist such torsional moments, and to prevent any such tendency to pull the frame askew. All such tendency is eventually resisted by the securement of the casing elements 18.

It may be observed at this point that a frame having parts interfitted as illustrated in Figure 2 or 3 need not be handled and applied as a complete unit, but may be installed one part at a time.

The first step is the installation of the hinge jamb 1, and after that has been installed as described, the head jamb 3 may be applied to its upper end, and then the side jamb 2 may be applied and installed, as will now be described.

As has been indicated by the dash lines in Figure 3, the frame elements 2 and 3 may now be out of plumb, but the opposite side jamb 2 is now plumbed and secured by the screws 6 and springs 23, such relative adjustment in spacing between the two side jambs being permitted by the hori-

zontal lost motion connection between the upper end of the side jamb 2 and the corresponding end of the head jamb 3 which rests upon it. This lost motion connection, in this form, consists of an angled clip, having in this location an upright arm 26 which is secured to the back face of the jamb 1, and having a resilient horizontal arm 27 which overlies and presses downwardly the overlying end of the head jamb 3, to preclude separation between the jambs 1 and 3.

A similar lost motion connection is provided at the right end of the head jamb 3 between itself and the upper end of the side jamb 2. The clip 26, 27 in this instance is secured to the head jamb 3, and serves to hold the abutting upper end of the side jamb 2 against separation from the abutted end of the head jamb 3, yet to permit relative vertical adjustment. The header 28 is sufficiently spaced above the head jamb 3 to permit this.

The jamb 2, carrying the striker plate 17, will be of such length, relative to the jamb 1 and the door 9, that if the floor is level and the lower end of the jamb 2 rests upon the floor, the striker plate 17 will be in alignment with the latch element 16. The opening in the striker plate 17 which receives the latch element 16 will normally be of somewhat greater length vertically than the exact size deemed necessary to receive the latch element. This will permit the proper operation of the latch in event the floor is not exactly level. However, if the floor should be out of level to an extent greater than what would be provided for by the size of the opening in the striker plate, then some alteration in the length of one of the side jambs would have to be made. If the jamb 1 was sawed off to reduce the floor clearance, the jamb 2 would, of course, have to be sawed off also.

Normally it is desirable to install the door frame after the finish floor has been laid and to rest the lower ends of the side jambs upon this floor. If for any reason, the door frame is to be installed before the finish floor is laid, this fact should be taken into consideration when computing the relative lengths of the side jambs and the door, and care should be taken in locating the side jambs vertically to provide the desired clearance between the bottom edge of the door and the surface of the finish floor when it is laid.

A door frame such as described above should be manufactured in the shop or factory, the door cut square and to size, and the hardware fitted, though not necessarily installed. Parts may be left unassembled for ease of handling until brought to the site of installation. Installation, then, is merely placing parts back in one homogeneous assembly, into the relative positions they occupied in the factory, either actually or potentially, and hence parts can be fitted exactly and quickly by installing them as already described.

While simplicity and ease of installation is the primary aim, nevertheless it will be recognized that, because of the manner of assembling, it is a simple matter, if the door swells or shrinks, or the building settles, and if through any such reason the door later fails to fit properly, to adjust the jambs as required to fit the door. If the door stops are formed as part of the frame, no adjustment nor trimming of these will be necessary, and even if they are separately installed after installation of the door frame, it will almost never be necessary to trim these in order to refit them to the frame.

I claim as my invention:

1. A frame construction for closures, comprising two spaced upright side jambs and a connecting head jamb, hinge mounting means carried by one side jamb, a non-yieldable spacer and securing means connecting adjacent studding to the upper end of the hinge-carrying jamb, to mount the latter in definite, fixed relationship to said studding, means mounting the remainder of the hinge-carrying jamb upon the studding in plumb position, adjustable securing means connecting one end of the head jamb to the upper end of said hinge-carrying jamb, the head jamb being adjustable only in the direction of its length relative to the hinge-carrying jamb, to adjust the width of the frame, adjustable securing means connecting the opposite end of the head jamb to the upper end of the other side jamb, the thus-connected head and side jambs being adjustable only vertically relative to each other, to level the head jamb, and means to support the second side jamb from the adjacent studding, in substantially plumb position, spaced from the hinge-carrying jamb the width of a door plus desired clearance.
2. A frame construction for closures comprising a sill, a top jamb, complementary side jambs, means adjustably connecting said complementary side jambs at their lower ends to opposite ends respectively of said sill, and one thereof at its upper end to one end of said top jamb, said connecting means providing for limited adjustment of the distance at both top and bottom between said complementary side jambs, means adjustably connecting the other side jamb at its upper end to the top jamb, for limited adjustment of the distance between this end, only, of said top jamb and said sill, and adjustable means fastening said frame construction to studding defining an opening in a wall, said adjustable means comprising a plurality of screw means extending through each of said side jambs and operatively engaging said studding and resilient means interposed between said side jambs and said studding, said resilient means serving to yieldably separate said side jambs from said studding.
3. A door frame construction comprising a top jamb, complementary side jambs, one whereof is fitted to support the door hinges, and is of a length between the floor level and its upper end exactly corresponding to the height, plus desired clearances, of the hinged edge of the door to be hung, one end of the top jamb resting upon the upper end of the hinge-mounting jamb, and the opposite side jamb extending past and abutting the other end of the top jamb, when its lower end rests upon a support at or near floor level, means securing the side jambs to adjacent studding, means joining them to the top jamb for adjustment of their spacing from one another at top and at bottom, to fit the door, and means adjustably securing that end of the top jamb which is remote from its end which is supported upon the hinge-mounting jamb, for adjustment vertically relative to the side jamb at this end, to afford desired clearance for the outer upper edge of the door.
4. A frame construction for closures, comprising two spaced upright side jambs and a connecting head jamb, means securing a first side jamb in plumb position to adjacent studding, adjustable securing means connecting one end of said head jamb to the upper end of said first side jamb, the head jamb being adjustable only in the direction of its length relative to said first side

jamb, to adjust the width of the frame, adjustable securing means connecting the opposite end of the head jamb to the upper end of the second side jamb, the thus-connected head jamb and second side jamb being adjustable only vertically relative to each other, to level the head jamb, and means to support the second side jamb from the adjacent studding, in substantially plumb position, spaced from the first side jamb the width of a door plus desired clearance.

5. A frame construction for closures comprising a top jamb, complementary side jambs, means adjustably connecting a first side jamb at its upper end to one end of said top jamb, for limited adjustment of the spacing between said two side jambs, means adjustably connecting the second side jamb at its upper end to the top jamb, for limited adjustment vertically of this end, only, of said top jamb relative to the second side jamb, and means to secure the jambs to adjacent studding in such relatively adjusted positions.
10. 6. A frame construction as in claim 5, including also a sill, and means adjustably connecting the sill and the lower ends of the respective side jambs for adjustment of the spacing only of such lower ends of the side jambs, but supporting the side jambs upon said sill.

15. 7. A frame construction as in claim 5, including also a sill, the lower ends of the side jambs being each transversely channeled across their inner faces to receive the respective ends of the sill, for support of the side jambs from the sill, but of a depth to permit limited adjustment of the spacing of the lower ends of the side jambs.
20. 8. A frame construction for closures, comprising two spaced-apart side jambs, a top jamb one end whereof overlies a first side jamb, and the opposite end whereof abuts the inside face of the second side jamb, means adjustably connecting the top jamb and the first side jamb for limited horizontal adjustment, only, of the top jamb relative to said first side jamb, to vary the spacing between the two side jambs, means adjustably connecting the top jamb and the second side jamb for limited vertical adjustment, only, of this end of the top jamb relative to said second side jamb, and means to secure the jambs in their relatively adjusted position to adjacent studding defining an opening in a wall.
25. 9. A frame as in claim 8, characterized in that a hinge seat is formed on that side jamb whereon rests one end of the head jamb.

30. 10. A frame construction as in claim 8, wherein the first side jamb carries a hinge seat for hinge support of a door, the jamb securing means therefor including a spacer between and preventing approach of said first jamb and the studding, and supporting elements spaced along the jamb from said spacer for adjustment of such first jamb about said spacer as a fulcrum.
35. 11. A frame construction as in claim 3 wherein the supporting elements yieldably urge the jamb away from the studding, and include means drawing the jamb towards and fixing it against separation from the adjacent studding.
40. 12. A frame construction as in claim 3, wherein the supporting elements comprise compression springs interposed between the hinge-mounting jamb, and screws extending through the jamb and received in the adjacent studding.
45. 13. A frame construction as in claim 12, characterized in that the means connecting the ends of the head jamb to the respective side jambs are formed as angled clips having one arm secured to and arranged generally in prolongation of one

jamb, and a second arm overlying the connected jamb and resiliently engaging the latter to hold it slidably to the end of the clip-supporting jamb.

14. A frame construction as in claim 12, characterized in that the means connecting the ends of the head jamb to the respective side jambs are formed as headed studs received in the abutted end of each jamb and passing through holes in the abutting face of the adjoining jamb, said soles being oversize for slidable adjustment 10 lengthwise of the thus-pierced jamb.

15. A frame construction as in claim 12, characterized in that the means connecting the ends of the head jamb to the respective side jambs comprise, an extension on the abutted end of a 15 jamb overlying the end of the abutting jamb, and dowel means projecting from the thus overlaid end of the abutting jamb, said extension having

holes snugly receiving said dowel means to prevent relative adjustment of the connected jambs laterally of the dowel means, but said extension being adjustable axially of the dowels.
